US0D1093298S

(12) **United States Design Patent** (10) **Patent No.:** **US D1,093,298 S**
(45) **Date of Patent:** **** Sep. 16, 2025**

(54) **CHARGING DEVICE FOR A COMPUTING DEVICE**

(71) Applicant: **Urban Armor Gear, LLC**, Laguna Niguel, CA (US)

(72) Inventor: **Evan Hong**, Murrieta, CA (US)

(73) Assignee: **Urban Armor Gear, LLC**, Laguna Niguel, CA (US)

(**) Term: **15 Years**

(21) Appl. No.: **29/898,274**

(22) Filed: **Jul. 25, 2023**

(51) LOC (15) Cl. **13-02**

(52) U.S. Cl.

USPC **D13/108**

(58) **Field of Classification Search**

(57) **CLAIM**

The ornamental design for a charging device for a computing device as shown and described herein.

DESCRIPTION

FIG. 1 is a front perspective view of a charging device for a computing device showing my new design;

FIG. 2 is a front elevation view of the charging device for a computing device illustrated in FIG. 1;

FIG. 3 is a rear elevation view of the charging device for a computing device illustrated in FIG. 1;

FIG. 4 is a side elevation view of the charging device for a computing device illustrated in FIG. 1;

FIG. 5 is an opposite elevation view of the charging device for a computing device illustrated in FIG. 1.

FIG. 6 is a top plan view of the charging device for a computing device illustrated in FIG. 1; and,

FIG. 7 is a bottom plan view of the charging device for a computing device illustrated in FIG. 1.

Any broken lines in the drawings illustrate portions of the charging device for a computing device that form no part of the claimed design.

1 Claim, 5 Drawing Sheets
